UNITED STATES PATENT OFFICE.

ALFRED HEALD, OF PHILADELPHIA, PENNSYLVANIA, ASSIGNOR TO HUGH McCALLUM, ORLANDO CREASE, ANDREW J. SLOAN, AND WILLIAM McCALLUM, OF SAME PLACE.

DESIGN FOR CARPET.

Specification forming part of Design No. 7,346, dated March 31, 1874; application filed March 25, 1874.
 [Term of Patent 3½ years.]

R.

To all whom it may concern:

Be it known that I, ALFRED HEALD, of Philadelphia, Pennsylvania, have invented a Design for a Carpet-Pattern, of which the following is a specification:

The figure in the accompanying drawing shows sufficient of a carpet-pattern to fully illustrate my design, the remainder being merely a repetition of that which appears.

A band or ribbon, A, extends throughout the entire pattern, and is curved and bent at various angles, as shown, so as to form borders for the ornamental figures B, C, D, and E. The figure B is the largest of the series, and has an ornamental outline, partly straight and partly curved, and an elaborate internal foliated ornament, a. The figure C is octagonal, and has a central ornament, b. The oblong figure D has a central foliated ornament, c. The figure or medallion E is circular, or nearly

circular, in outline, and has a central ornament, e. The space between the several figures is elaborately ornamented by a wreath, f, composed of flowers, leaves, and stems, arranged as shown.

Irrespective of the colors employed, I claim—

1. The design for the figure B, with its central ornament a, as shown and described.

2. The design for the whole pattern, including the band or ribbon A, the figures B, C, D, and E, and the intervening space with its wreath f, all as described, and as represented in and by the accompanying drawing.

In testimony whereof I have signed my name to this specification in the presence of two subscribing witnesses.

ALFRED HEALD.
